UNITED STATES PATENT OFFICE

JOHN F. MEYER, OF CHICAGO, ILLINOIS

DESIGN FOR AN AMUSEMENT-MACHINE CASING

Application filed November 27, 1929. Serial No. 33,565. Term of patent 14 years.

To all whom it may concern:

Be it known that I, JOHN F. MEYER, a citizen of the United States, residing at Chicago, in the county of Cook and State of Illinois, have invented a new, original, and ornamental Design for Amusement-Machine Casing, of which the following is a specification, reference being had to the accompanying drawing, forming a part thereof, in which the figure is a perspective view of the amusement-machine casing, showing my new design.

I claim:

The ornamental design for an amusement machine casing, as shown.

JOHN F. MEYER.
